UNITED STATES PATENT OFFICE.

ISAAC A. PERRY, OF WILMINGTON, DELAWARE.

RAILWAY-FROG.

SPECIFICATION forming part of Letters Patent No. 380,923, dated April 10, 1888.

Application filed July 16, 1887. Serial No. 244,439. (No model.)

To all whom it may concern:

Be it known that I, ISAAC A. PERRY, a citizen of the United States, and a resident of Wilmington, New Castle county, Delaware, 5 have invented certain Improvements in Railway-Frogs, of which the following is a specification.

My invention consists of certain improvements in the railway-frog for which I obtained 10 Letters Patent No. 313,368, dated March 3, 1885, the main object of my invention being to so construct the frog as to facilitate the renewal or repairs of parts of the same, and to effect the secure confinement of the frog-point 15 and the rails forming continuations of the same.

In the accompanying drawings, Figure 1 is a plan view of my improved frog. Fig. 2 is a longitudinal section of the same on the line 20 1 2, Fig. 1. Figs. 3, 4, 5 and 6 are transverse sections respectively on the lines 3 4, 5 6, 7 8, and 9 10, Fig. 1. Fig. 7 is a perspective view of the parts composing the frog detached from each other, and Fig. 8 is a view illustrating a special construction of part of the frog. 25

A represents the base-plate or foundation of the frog, which may be of wrought or cast iron or steel, and which has formed in it openings a, b, and d. To the opening a is adapted a 30 tongue, f, on the under side of a plate, B, which plate has a recess, g, for the reception of the nose of the frog-point D, the recess having overhanging walls which engage with the flange D' at the base of said point and serve to vertically retain the same. The tongue f has at the front end a toe, f', which engages with the base-plate A, and said tongue is retained in position in the recess a by means of a transverse key, c, passing through the tongue 35 and bearing against the under side of the base-plate. The point D has a projecting tongue, h, adapted to the opening b in the base-plate, and a second tongue, i, which is adapted to the front end of the opening d in said plate and 40 to an opening, i', in a plate, F, which rests upon the base-plate A and serves to support the rear end of the point D and the rails G G, which form continuations of said point, the inner treads and flanges of these rails being 45 cut away, so as to permit the webs of the rails to meet each other where the rails join the 50

point D, said webs forming a projecting tongue, j, which enters a recess or pocket, j', in the rear end of the point, as shown in Fig. 2. The plate F likewise has a tongue, m, entering the 55 opening d in the base-plate, and both of the tongues i and m are confined to said base-plate by means of a transverse key, n, passing through the tongues, through lateral recesses n' in the base-plate, and beneath lugs H, secured to said base-plate near each edge of the same.

The tongue m of the plate F has at the rear end a toe, m', engaging with an undercut portion of the base-plate A, and the front ends of the lugs H are likewise undercut, as shown 60 in Fig. 7, for the reception of undercut portions H' on the plate F.

Longitudinal movement of the plate F, as well as any vertical movement of the front end 70 of the same, is resisted by retaining-keys p, adapted to recesses p' in the front edge of said plate, these keys being preferably held in place by wedges s, as shown in Fig. 1.

While the retaining-plate B, supporting 75 plate F, and point D are thus firmly locked to the base-plate of the frog, any one of said parts can be detached from the base-plate when desired, and either part can be repaired or replaced without necessitating the renewal of 80 any other part.

The supporting-plate F has an inclined filling-piece, I, which fits between the diverging rails G G, so as to maintain the same at the proper distance apart, said filling-piece having flanges overlapping the inner flanges of 85 the rails and serving to vertically confine the same to the plate F.

The outer flanges of the rails are confined by means of flanged wedge-plates J J, which are 90 adapted to inclined grooves K K, formed in the supporting-plate F, so that on driving up these wedges the rails will be firmly pressed against the central filling piece or block and will be rigidly confined to the plate F. The 95 front ends of the wedge-plates J J have portions J' for bearing upon the opposite inclined sides of the point D of the frog and aiding in the retention of the same; but these portions J' may, if desired, be made separate from the 100 plates J, or may be dispensed with altogether.

When the structure is so placed that one of

the rails G is subjected to excessive strain, the plate J for retaining the same is preferably provided with a tongue, t, projecting under the supporting-plate F and engaging with an undercut recess in the under face of the same, as shown in Fig. 8, so as to effectually resist any rising tendency of the lower flange of the rail due to excessive lateral pressure upon the head of the same, it being understood that the recess is inclined in the same manner as the recess K, so that the lateral confinement of the rail is effected by imparting longitudinal movement to the wedge-plate.

I claim as my invention—

1. The combination, in a railway-frog, of the base-plate, the point having tongues engaging with openings in said base-plate, and a detachable retainer for the nose of the point, said retainer having a tongue adapted to an opening 20 in the base-plate and provided with a toe projecting beneath said plate, all substantially as specified.

2. The combination of the base-plate, the point of the frog, the retainer-plate therefor, recessed for the reception of said point and having a tongue adapted to an opening in the base-plate, and a transverse key whereby said tongue is secured to the base-plate, all substantially as specified.

3. The combination of the base-plate of the frog, the point, and the point-supporting plate having a tongue adapted to an opening in the base-plate, said tongue being provided with a toe engaging with the base-plate and held in engagement therewith by contact of the point with the supporting-plate, all substantially as specified.

4. The combination of the base-plate, the point and its supporting-plate, both having 40 tongues adapted to a recess in the base-plate, with a transverse retaining-key confined to the base-plate and passing through the tongues of the point and its supporting-plate, so as to retain them both, all substantially as specified.

5. The combination of the base-plate of the frog, having an opening therein and lugs H thereon, with the supporting-plate constructed to engage with said lugs, and having a tongue for adaptation to the opening in the base-plate, all substantially as specified.

6. The combination of the base-plate of the frog and its lugs, the supporting-plate mounted on said base-plate and engaging with said lugs, and keys engaging with the front end of the supporting-plate and retaining the same in position for engagement with said lugs, all substantially as specified.

7. The combination of the base-plate, the point having a recess or pocket in the rear end, and diverging rails forming a continuation of 60 the point, and having their treads and flanges cut away on the inner side to permit the approach of the webs and the formation of tongues entering said pocket in the point, all substantially as specified.

8. The combination of the point of the frog and the diverging rails forming a continuation of the same, the supporting-plate, means for securing the point thereto, a filling-piece interposed between the rails, and wedge-plates 70 engaging with the outer flanges of the rails and adapted to inclined ways in the supporting-plate, all substantially as specified.

9. The combination of a rail and a supporting-plate therefor, with a retaining-plate engaging with the flange of the rail and having a tongue projecting beneath the supporting-plate and engaging with an inclined way in the under side of the same, all substantially as specified.

In testimony whereof I have signed my name to this specification in the presence of two subscribing witnesses.

ISAAC A. PERRY.
